(57) **CLAIM**

The ornamental design for a removable jar of a battery-powered portable blender, as shown and described.

DESCRIPTION

FIG. 1 is a top-front-left perspective view of a removable jar of a battery-powered portable blender showing the new design;

FIG. 2 is a front view thereof;

FIG. 3 is a rear view thereof;

FIG. 4 is a left view thereof;

FIG. 5 is a bottom view thereof;

FIG. 6 is a top view thereof;

FIG. 7 is a top-rear-right perspective view thereof;

FIG. 8 is a top-rear-left perspective view thereof;

FIG. 9 is a bottom-front-left perspective view thereof;

FIG. 10 is a bottom-rear-right perspective view thereof; and,

FIG. 11 is a bottom-rear-right perspective view showing another implementation of the new design for the removable jar of a battery-powered portable blender.

The portions shown in broken lines form no part of the claimed design.
